UNITED STATES PATENT OFFICE.

CARL L. NOHLEN, OF CLEBURNE, KANSAS.

JETTY AND UNIT THEREFOR.

Application filed December 9, 1926. Serial No. 153,631.

This invention relates to means for protecting the banks of rivers and streams from erosion and to cause the filling in of silt and like material at any particular point along 5 a river bank and the invention particularly relates to the construction of jetties for this purpose.

The general object of the present invention is to provide a unit which may be 10 combined with other units of like character to form a jetty which is capable of being readily anchored to the shore, which will form a sufficient obstruction as to cause the deposit of silt and sand and which is so 15 constructed that there are no cross bars to be bent out of shape by ice or floating logs or trees.

A further object is to provide a jetty unit 20 of such shape that hog fencing or like material may be wrapped around the unit, which helps the unit from sinking out of sight in quicksands.

A still further object is to provide a jetty unit of a generally spherical but open work 25 character so that the jetty will fit to some extent the shape of a river bank and thus prevent the bank from washing away between the face of the bank and the first jetty unit, and a further object in this connection 30 is to form a jetty unit of hoops, these hoops acting to brace each other without the use of cables and these hoops permitting the jetty units to be formed with or without prongs.

35 Other objects will appear in the course of the following description.

My invention is illustrated in the accompanying drawings wherein:—

Figure 1 is a diagrammatic illustration of 40 my device in applied position;

Fig. 2 is a sectional view thereof;

Fig. 3 is a sectional view of one of the jetty units;

Fig. 4 is a modified construction of one 45 of the hoops;

Fig. 5 is a similar view to Figure 4, but showing a modification of the construction illustrated in Figure 4;

Fig. 6 is a detailed view of a modification 50 of the device.

Referring to these drawings it will be seen that each jetty unit A is constructed of preferably three hoops or rings 10, the three hoops being disposed with their planes at 55 right angles to each other so as to consti-

tute a hollow, open work sphere. These hoops are formed of flat iron or steel bars. They can also, however, be made of round iron bars, pipes, channel iron bars, angle irons, or bars of any other desired cross 60 sectional shape.

When a small jetty is to be made, the open work balls or units will be formed with their hoops each of a single strip of iron or steel arranged together, as shown in Figure 65 3, but it will be understood that where larger hoops are to be used, the hoops will be formed of two, three or four pieces or strips, as shown in Figure 4. Where the balls are relatively large, it will be obvious that it is 70 easier to make them of relatively small sections bolted to each other than it would be to handle one strip or bar of a length sufficient to form a large hoop. Under some circumstances and in non-navigable streams, 75 it is advisable to provide prongs on the balls or jetty units and to this end, as shown in Figure 5, each of the hoops is formed with the prongs 11. Under these circumstances, 80 the hoops of each unit are formed in sections 12 and the point of attachment to the next adjacent section is inward of the end of the section so as to leave the prongs 11 projected. It will be understood, however, 85 that the prongs might be formed in other ways as, for instance, the prongs may be formed by strips or bars 13 riveted or bolted at two points to the hoop and having their ends 14 projecting upward.

The style of jetty shown in Figure 3 may be used in navigable streams as there are no cross bars or prongs to punch holes through the bottoms of boats. The prongs, where they are used, help to anchor the jetties and also to catch trash, etc. Where sufficient anchorage cables are used, the jetty unit without the prongs can be used.

In Figure 1 I have illustrated how these jetty units are to be used. The jetty is shown as constructed of five units held to the river bank B by the anchoring cables 15 and 16 and the anchors 17. The cables 16 are connected to the outermost units while the cables 15 are carried from the innermost unit 100 or units directly to the river bank. The cables 16 prevent the jetty from swinging.

It will be seen from Figure 2 that the spherical shape of the jetty units permits them to be brought up close to the bank and 110

fit against the face thereof. These jetty units form a retard which breaks up the force of the current and causes the deposit of silt and sand along the bank as, for instance, at C. This keeps the bank built up. Obviously as many jetty units may be used or as many jetties may be disposed along the bank as required.

It will be seen that the jetty units are relatively light, that they can be readily put together and easily handled, and that they may be covered with wire netting as, for instance, hog fencing, so as to keep them from sinking out of sight in quicksands or in like places. Inasmuch as the jetty units are spherical in form, there are no sharp angles or points which will be liable to punch holes in the bottoms of boats and they will tend to roll when struck. There are no cross bars or other like elements which would tend to damage boats accidentally striking the jetties. The prongs used upon the units in non-navigable streams help to anchor the jetty unit in place and help also to catch trash, such as floating branches, weeds, and the like, so as to aid in retarding the current and aid in the deposit of silt.

While I have illustrated certain preferred embodiments of my invention, I do not wish to be limited thereto, as it is obvious that many changes might be made in the details of construction and arrangement of parts

without departing from the spirit of the invention as defined in the appended claims.

I claim:

1. A jetty unit consisting of a plurality of circular hoops intersecting each other at different angles and rigidly connected to each other to form an open work sphere. 35

2. A jetty unit consisting of a plurality of circular hoops intersecting each other at different angles and rigidly engaged with each other, certain of the hoops being formed with outstanding prongs. 40

3. A jetty unit consisting of a plurality of circular hoops intersecting each other at different angles and rigidly engaged with each other, the ends of certain of the hoops being deflected outward to form prongs. 45

4. A jetty unit consisting of at least three circular metal hoops, the hoops intersecting each other at right angles to define a sphere and being rigidly engaged with each other. 50

5. A jetty consisting of a plurality of open work spherical units arranged in line from a river bank, cables connecting the several units to each other and to the shore, and cables connecting the outermost units to the shore and extending at an angle to the first named cables. 55

In testimony whereof I hereunto affix my signature.

CARL L. NOHLEN.
